UNITED STATES PATENT OFFICE.

SIGMUND FISCHER, OF PROVIDENCE, RHODE ISLAND.

UNIT FOR USE IN THE MANUFACTURE OF SEPARABLE CUFF LINKS.

Application filed April 18, 1927. Serial No. 184,776.

My invention relates to separable buttons, particularly to separable cuff links and comprises a unit relatively easy to manufacture for use in the production thereof. An object of my invention is to simplify the manufacture of separable cuff links and to provide a construction the parts of which may be readily stamped out of sheet material. In its complete form my invention comprises a unit comprising a top plate having holes, preferably two disposed in diametrically opposite sides thereof, a bottom plate of any desired configuration having holes, preferably two disposed at diametrically opposite sides thereof and a shank, preferably flat having upper and lower edges, preferably obliquely disposed with said top and bottom plates firmly secured thereto, preferably by means of the upset ends of lugs projecting integrally from the upper and lower edges of said shank through said diametrically disposed holes. It is apparent that two of these units form a set of cuff links and that the top plate of each link is adapted to have a separable fastener unit attached thereto and the bottom plate is adapted to have a suitably ornamented base attached thereto. Hitherto in the manufacture of separable cuff buttons, the head has been formed integral with the shank, which has necessitated complicated rolling and pressing operations. With my new mode of attachment the top plate is constructed separately from the shank and all three portions of my unit may be readily quickly stamped on a pressing machine and as quickly coupled together. The top plate and shank form a separate unit to which a bottom plate of any desired configuration to receive any desired shape of ornament may be readily and quickly attached.

These and such other objects of my invention as may hereinafter appear will be best understood from a description of one embodiment thereof such as is shown in the accompanying drawings.

In the drawings, Fig. 1 is a side elevation of a complete unit constructed in accordance with my invention.

Fig. 2 is a disassembled perspective view thereof.

Fig. 3 illustrates alternative forms of bottom plates, which may be employed.

Fig. 4 is a side elevation illustrating the means I preferably employ to upset the ends of the lugs to firmly attach the top plate to the shank.

Fig. 5 is a plan view of my invention.

Fig. 6 is a reverse plan view thereof.

Fig. 7 is a side elevation of the two units of my invention necessary to make a separable cuff link showing the relative position they assume in use.

In the drawings, wherein like characters of reference indicate like parts throughout, 10 generally indicates a suitable top plate. 65 As stated said top plate is adapted to have either the male or female portion of a separable fastener attached thereto, and therefore is provided with the cup depression 12 to receive if desired the female socket of a 70 separable fastener. 14 are two suitable holes which may be formed if desired in the stamping operation, and preferably disposed on diametrically opposite sides thereof for a purpose to be described later. 16 is a suitable 75 bottom plate, which also preferably has two holes 18 disposed on diametrically opposite sides thereof. The bottom plate is adapted to have attached thereto the desired type of ornament and is provided with the hole 20 80 or other means, whereby said ornament may be readily attached thereto. As will be apparent my invention is adapted to receive any desired shape of bottom plate such as the octagonal bottom plate 16 shown in Fig. 85 2, the round bottom plate 16^a or the oval bottom plate 16^b shown in Fig. 3.

It is obvious that the bottom plate may be readily stamped in a single operation and have the holes 18 and 20 suitably pierced 90 therein. To join said top and bottom plates together I provide the shank 22 which as shown in my preferred embodiment is preferably flat and which has the upper and lower edges 24 and 26 thereof preferably 95 obliquely disposed relative to each other so that when the unit is assembled and has the other parts of a cuff link attached thereto the flat shanks 22 will normally fit in the slits in the cuffs and the cuff link bases will be 100 held at an angle to each other. The upper edge 24 is provided with the semi-circular open portion 27 to receive the depression 12 of the top plate 10. The upper edge 24 thereof is also provided with the lugs 28 105 equal in number to the holes 14 of the top plate 10, which project integrally from said shank 22 and which when inserted through the holes 14 are adapted to have the ends 30 thereof upset as at 32 so as to firmly couple 110 the top plate to the upper edge 24 of said shank. When the shank 22 and top plate 14

have been suitably stamped as hitherto explained the flat shank 22 may be suitably held in a holding clamp 31 comprising two halves suitably pivoted together by the pivot 5 pin 34 with the inside of one of both of said half portions suitably shaped as at 36 to receive the shank 22 so that the holding clamp may firmly retain said shank therein. With the shank suitably encased within said holding clamp the top plate 10 is then laid over the projecting lugs 28 of said shank, the upper ends 30 thereof projecting through said holes 14. A suitable riveting punch 38 is then brought in line with said lugs 28 and 10 lowered centrally thereof so as to upset the ends 30 thereof into the split upset elements 32 as shown in Fig. 5.

It is obvious that I have even at this point provided a novel unit comprising a shank 20 of novel configuration having a top plate suitably secured thereto in a novel fashion, the shank being provided with suitable means for attachment to the lower edge thereof any suitable configuration of bottom plate.

25 The lower edge 26 of said shank is provided with lugs 40 projecting integrally downwardly from the lower edge thereof adapted to be inserted through the holes 18 of the bottom plate 16. The shank 22 with 30 attached top plate 14 may then be inserted in another suitable holding clamp so as to have the lugs 40 projecting upwards therefrom in a manner similar to that hitherto explained for attachment of the top plate 35 10. A bottom plate 16 of the desired configuration may then be laid on top of said holding clamp so that the outer ends 42 of said lugs 40 project beyond and through the holes 18 in said bottom plate. The holding clamp may then be brought in line with 40 the suitable riveting punch, which is then pressed centrally of said ends 42 to split them outwardly into the retaining portions 44 to firmly retain said bottom plate to said shank 22.

45 As hitherto explained either the male or the female portion of a separable fastener may be attached to the top plate 10 as it is obvious that it is constructed to receive 50 either. If the female portion is employed the socket thereof is adapted to register in the depression 12. As stated hitherto the bottom plate 16 is so shaped as to have mounted thereon ornamentation of any desired style and configuration.

55 It is understood that my invention is not limited to the specific embodiment shown and that various deviations may be made therefrom without departing from the spirit 60 and scope of the appended claims.

What I claim as new and desire to secure by Letters Patent is:

65 1. A unit for use in the manufacture of separable cuff links comprising a top plate having two holes disposed on diametrically

opposite sides thereof, a bottom plate of any desired configuration having two holes disposed on diametrically opposite sides thereof, and a flat shank having obliquely disposed upper and lower edges having lugs 70 projecting integrally from the upper and lower edges of said shank through said diametrically disposed holes, said top and bottom plates being firmly secured to said shank by the upset ends of said lugs. 75

2. A unit for use in the manufacture of separable cuff links comprising a top plate, a bottom plate of any desired configuration and a shank having obliquely disposed upper and lower edges having said top and 80 bottom plates firmly secured thereto.

3. A unit for use in the manufacture of separable cuff links comprising a top plate having two holes disposed on diametrically opposite sides thereof and a flat shank having obliquely disposed upper and lower edges, the upper edge having two spaced lugs projecting integrally from the upper edge thereof through said diametrically disposed holes, said top plate being firmly secured to said shank by the upset ends of said lugs and the lower edge thereof having two spaced lugs projecting therefrom adapted to project through two diametrically disposed holes in a base plate of any desired 90 configuration and to have the ends thereof upset to retain said base plate to said lower edge. 95

4. A unit for use in the manufacture of separable cuff links comprising top plate and a shank having obliquely disposed upper and lower edges, the upper edge having said top plate firmly secured thereto and the lower edge thereof having spaced lugs projecting therefrom adapted to project through holes 100 in a base plate of any desired configuration and to have the ends thereof upset to retain said base plate to said lower edge. 105

5. A unit for use in the manufacture of separable cuff links comprising a top plate 110 having holes therein, a bottom plate of any desired configuration having holes therein and a shank having upper and lower edges having lugs projecting integrally from the upper and lower edges of said shank through said holes, said top and bottom plates being firmly secured to said shank by the upset ends of said lugs. 115

6. A unit for use in the manufacture of separable cuff links comprising a top plate 120 having holes disposed on diametrically opposite sides thereof and a shank having upper and lower edges, the upper edge having spaced lugs projecting integrally from the upper edge thereof through said diametrically disposed holes, said top plate being firmly secured to said shank by the upset ends of said lugs and the lower edge thereof having spaced lugs projecting therefrom adapted to project through diametrically 125 130

disposed holes in a base plate of any desired configuration and to have the ends thereof upset to retain said base plate to said lower edge.

5 7. A unit for use in the manufacture of separable cuff links comprising a top plate having a central cup depression therein and a plurality of holes on the outer edge thereof exterior of said depression and a shank having upper and lower edges, the upper edge having lugs projecting integrally from the upper edge thereof through said holes and a central open portion to receive the cup depression of said top plate therein and the 10 lower edge thereof having means for attachment thereto of a bottom plate.

15 8. A unit for use in the manufacture of

separable cuff links comprising a top plate having a central cup depression therein and two holes disposed on diametrically opposite sides thereof exterior of said depression and a flat shank having obliquely disposed upper and lower edges, the upper edge having said top plate firmly secured thereto by the upset ends of lugs projecting integrally from the upper edge thereof through said diametrically disposed holes and a central open portion to receive said cup depression of the top plate therein and the lower edge thereof having means for attachment thereto of a bottom plate.

In testimony whereof I affix my signature.

SIGMUND FISCHER.
